United States Patent Office.

J. M. TANNER, OF ALBERT LEA, MINNESOTA.

Letters Patent No. 73,850, dated January 28, 1868.

IMPROVEMENT IN WATER-WHEELS.

The Schedule referred to in these Letters Patent and making part of the same.

TO ALL WHOM IT MAY CONCERN:

Be it known that I, J. M. TANNER, of Albert Lea, in the county of Freeborn, and State of Minnesota, have invented a new and useful Improvement in Water-Wheel; and I do hereby declare that the following is a full, clear, and exact description thereof, which will enable others skilled in the art to make and use the same, reference being had to the accompanying drawings, forming part of this specification, in which—

Figure 1 is a horizontal sectional view of my improved water-wheel.

Figure 2 is a vertical section of the same, taken through the line *x x*, fig. 1, showing the friction-rollers, and the eccentric path in which they work.

Figure 3 is a vertical section of the same, taken through the line *y y*, fig. 1, showing the pivoted guide-arms to which the buckets are attached.

Figure 4 is a vertical sectional view of the same, taken through the line *z z*, fig. 1, showing the slots in which the curved buckets work.

Similar letters of reference indicate like parts.

My invention has for its object to furnish an improved water-wheel, simple in construction, effective in operation, and not liable to get out of order; and it consists in the thin curved buckets attached to the ends of pivoted arms working in cavities in the heads of the wheel, and operated and guided by wrist-pins, or by friction-wheels or rollers, pivoted to said arms, and working in eccentric grooves in the casing of the wheel, the whole being constructed and arranged as hereinafter more fully described.

A is the body of the water-wheel, in the face of which are formed any desired number of longitudinal slots, for the ingress and egress of the buckets *B*, the number of which will, in each case, depend upon the size of the wheel, the amount of power required, &c. The buckets *B* are made thin and curved, and pass into and out of the body *A* of the wheel, through the slots in its face. The ends of the buckets *B* pass through and work in curved slots in the end or head-plates *C*, and their ends are secured to the ends of the pivoted arms *D*. In case the wheel *A* be made of wood, the face of said wheel, at the edges of the slots through which the buckets *B* pass in and out, may be faced with thin iron plates, to prevent their enlargement by the friction and wear of the said buckets. If found advisable, a strip of rubber may also be inserted in said slots to serve as packing, to prevent the water from flowing into the interior of the wheel *A*. The arms *D* are pivoted in the recesses formed in the ends or heads of the wheel, or between the two ends or head-plates *C* and *E*. The space between the head plates *C* and *E*, with the exception of the recesses in which the pivoted arms *D* work, may be filled with a solid framework, *F*, or the said recesses may be formed by flanges formed upon one of the plates, *C* or *E*. To the ends of the arms *D* are attached wrist or guide-pins, *G*, which enter and work in eccentric grooves formed in the casing *H* of the wheel, which said grooves are so formed, that, as the guide or wrist-pins *G* move along them, the buckets *B* will be forced out at the proper time to receive the impulse of the water, and again withdrawn into the body of the wheel *A*, when said impulse has expended its force, so as to be out of the way of the casing *H* during the remaining part of the revolution of the wheel. The drawings represent the wheel as being attached to a horizontal shaft, but this is immaterial, the wheel being so constructed as to operate equally well in any position, according as the circumstances of each case may render advisable. *I* are friction-wheels or rollers, placed upon the guide or wrist-pins *G*, and which roll along the eccentric grooves, so as to diminish the friction in operating the wheel.

I claim as new, and desire to secure by Letters Patent—

1. The combination of the centrally-pivoted arm *D*, movable buckets *B*, and body *A*, all arranged and operating as herein described, for the purpose specified.
2. The thin curved buckets *B*, attached to the ends of arms *D*, pivoted in recesses in the heads of the wheel *A*, and operated and guided by wrist or guide-pins *G*, or by friction-wheels or rollers, *I*, pivoted thereto, said pins or rollers working in eccentric grooves in the casing *H* of the wheel, substantially as herein shown and described, and for the purpose set forth.
